CLOSURE

Richard E. Phillips, Baton Rouge, La., assignor to Ethyl Corporation, New York, N.Y., a corporation of Virginia

Filed Sept. 28, 1962, Ser. No. 226,949
2 Claims. (Cl. 220—44)

This invention relates to closures. More particularly, this invention relates to closure devices for tanks or transport vessels for chemical liquids which require particularly careful handling in loading, unloading and in transmission generally.

In the transport of various chemical commodities having appreciable vapor pressures or of a toxic nature, relatively complicated devices have heretofore been used for the closures of openings of said tanks or vessels. Generally, the closure elements for a vessel include a vent line, a liquid line, and a safety or pressure relief line. In conventional apparatus, such as tanks found in railway tank cars, or tanks of highway tank units, each of said lines or openings to the interior of the tank includes a conduit and a valve associated therewith. Such valves, being necessarily mounted externally of the tank periphery or boundary, project into the surrounding space, and in order to prevent these from suffering damage in occasional accidents or even in the case of routine handling, they are positioned in a supplemental chamber or shell so that random blows can not strike the closure elements proper. The vertical space occupied by these closure arrangements adds to the cost and overall space requirement for a tank unit. The use of valved openings, particularly for the liquid transfer (charging or discharging) opening, and for the vent opening, is sometimes superfluous, in that in practically all receiving installations, provision is normally made for valved receiving conduits or venting conduits for matching up and connecting the said openings. Hence, in practice, in transport vessels fitted as outlined above, a dual valving system is, then, in fact in vogue. For large capacity tanks, or for tank units not necessarily intended for application in restricted modular space, the foregoing features are not highly disadvantageous, in that the cost of the valving and the space of the closure assembly is not particularly detrimental. However, the wider use of small capacity vessels, for example, which are not integrally applied to any transportation vehicle, such as a railway car or a highway trailer, but are intended for mounting on skids or pallets, and handling as such, the previously available closure assemblies are highly bulky, costly, and detrimental.

The object of the present invention is to provide a low cost, highly effective, and low profile closure assembly for tanks or vessels for use in transport and/or storage of chemical commodities, especially liquids. More particularly, an object of the present invention is to provide a closure assembly readily adapted and used with liquid transport tanks which incorporates lock-in or safety features which heretofore have been realized only by valving systems. Other objects will appear more specifically from the description and examples given hereinafter.

A typical and preferred embodiment of the invention is illustrated by the figures, of which

FIG. 1 is a plan view of a closure assembly of the present invention, and

FIG. 2 is an elevation view thereof.

The apparatus of the invention includes a flange like or base member for attachment and mounting on a large opening of a transport vessel or tank. Generally, such a flange member may correspond in gross dimensions to a conventional blind flange of the desired weight series for the service intended, and is attached to a flange member associated with a nozzle of the tank unit. Various

2

fastening means can be employed for attaching this blind flange or plate member to the tank opening.

In the above mentioned blind flange member, or base member, are at least two service openings in all forms of the invention, one of the service openings being an opening for liquid transfer and the other being an opening for vent or gas. For purposes of description, the opening for liquid is referred to herein as the first opening and the opening for gas is referred to as the second opening. It will be understood that other openings can be provided, and in particular, openings for pressure relief, associated with pressure relief discs or other relief elements, can be also included in the apparatus and incorporated into the base. Attached to the base member at the first opening is a dip leg or conduit member for extending to the interior of the tank to be serviced or for which the closure apparatus is intended. A first blind flange closure is provided, with means for attaching to the base member and closing of the first opening. A second blind flange or closure element is provided for closing the second opening in the base member, and also means for attaching the said member to the base, for securely closing the second opening. Associated with the second flange and affixed thereto is extension means projecting over the first opening and the closing means therefor, and barring the actuation of said closing means when the second closing means is itself in closed position.

Referring to FIG. 1, a plan of a particular embodiment is shown. The base element 11 is a conventional blind flange member adapted for attachment by conventional means to a corresponding flange member 12 associated with the tank and providing an opening in the tank wall 13. Fastening members 14 are provided for securing the base flange element 11 to the tank wall flange 12. Provided in the base are the first opening or aperture 15 and the second opening 28. Affixed to the base member 11 and communicating with the second opening 28 is a dip leg conduit 29, extending to the interior of the tank space for direct communication with any liquid therein. The first opening 28 and the second opening 15 are respectively closed by first and second, removable blind flange elements 30, 16. The design and construction of said flange closures or blind flanges can be conventional and usually will include tongues for mating with a corresponding gasket groove in the base 11. Threaded fastening means 31, 17 associated respectively with the first opening 28 and the blind flange closure therefor 30; and with the second opening 15 and the blind flange closure 16 therefor are provided.

Attached fixedly to the blind flange closure 16 for the vent aperture 15 is a transverse restraining apparatus protector or bar 18, which continues as or is attached to a cup guard 19, the dimensions thereof being such as to fully encompass the periphery of the blind flange 30 functioning as a closure for the first opening 28. Projecting from the cup 19 is a lug 20 which is positioned adjacent to a matching lug 21 permanently attached to the main flange 11, both having a hole for insertion of a lock member if desired.

The opposite extremity of the restraining bar 18 projects beyond the periphery of the blind flange 16 and engages a hinge member 22, attached to the base 11, by means of a pin 23 affixed to the extremity of the bar 18, and movably positioned in an elongated slot in the arms of the hinge member 22. The proportions of the slot 24 are such that, upon disengaging the fastening means 17, which position the second blind flange 16, that the entire assembly including the cup 19, bar 18, and blind flange 16 can be moved vertically to fully free the blind flange 16 from engagement with the studs of the threaded fastening means 17, said studs being fixedly attached to the main flange or base member 11. Upon this disengage-

ment, the said assembly can be swung back by rotation around the pin 23, and will thus expose the first blind flange 30 and the threaded fasteners 31 associated therewith, whereby the first opening 28 through the flange member can be opened, and appropriate connection made with the conduits provided at normal unloading or loading positions at consuming locations.

Apertures 32 can be provided in the cup 19, and said apertures are sized to prevent access to the threaded fastening means which secure the blind flange 30 in place, thus permitting visual inspection only.

The embodiment above described is, as noted, adapted for use when the fastening means, for securing the vent flange member in place, include studs permanently projecting from the base member. In other instances, when, for example, the fastening means are cap screws, there are no projecting studs. In such instances, the restraining bar 18 can be hinged to the base 11 by appropriate pin means, without the necessity of any vertical slide movement.

Having described my invention, what is claimed is:

1. Closure apparatus for liquid transport vessel, said apparatus including a base plate having service openings therein as hereinafter defined and adapted for covering a tank opening, said service openings including a first opening for liquid and a second or vent opening for gas, a dip leg conduit affixed to the base plate and extending from the liquid opening to communicate with the interior of the liquid of the transport vessel, a closure member for the first opening and a closure member for the vent opening, 30 and separate means for attaching said closure members to the said base plate member, and restraining means associated with the closure member for the vent opening whereby the closure member for the liquid opening can not be removed until the closure member for the vent 35 opening is removed.

2. Closure apparatus for a liquid transport or storage vessel, including a base plate or blind flange having service openings therein as hereinafter defined and adapted for covering a tank opening, said service openings including a first opening for liquid and a second or vent opening for gas, a dip leg conduit affixed to the base plate for projecting into the interior of the vessel from the first opening, a first blind flange closure for the first opening and threaded means for affixing said first blind flange closure to the base plate, a second blind flange closure for the second opening and threaded fastening means for securing said flange closure to close said second opening, and restraining means attached to said second blind flange closure for preventing disengagement of the blind flange closure means for the first opening until the second blind flange closure means is entirely removed, said restraining means including a bar member attached to the second blind flange closure and extending toward the locus of the first opening, and having a cup surrounding and surmounting the blind flange closure for the first opening, and a hinge means associated with said bar and located remotely from said cup, said hinge means including a pivot vertically slidably in a socket whereby release of the threaded fastening means affixing the second blind flange closure permits vertical movement of said restraining means to allow fully disengagement of the second blind flange closure from the threaded fastening means, and the establishment of accessibility of the first blind flange closure and the threaded fastening means therefor.
